UNITED STATES PATENT OFFICE.

ERWIN R. JONES, OF COLUMBUS, OHIO.

OPERATING DEVICE FOR VALVE GRINDERS.

1,421,486.

Specification of Letters Patent. Patented July 4, 1922.

Application filed May 29, 1919. Serial No. 300,777.

To all whom it may concern:

Be it known that I, ERWIN R. JONES, a citizen of the United States, residing at Columbus, in the county of Franklin and 5 State of Ohio, have invented certain new and useful Improvements in Operating Devices for Valve Grinders, of which the following is a specification.

The invention relates broadly to engine 10 tools, and has particular reference to valve grinders, the object of the invention being to provide a valve grinder of simple, efficient and economical construction which will be fully capable of carrying out its intended 15 functions in a reliable and labor saving manner.

In carrying out the invention, a valve 20 grinder is provided wherein is embodied a casing having a valve rotating stem journaled 25 therein, said stem being provided with a pair of fixed pinions which are disposed to be successively engaged by means of a rotating gear element, whereby upon the rotation of said element said valve stem will be alternately oscillated first in one direction and then in the opposite direction, in order that the necessary abrasive action may be imparted to the valve seat by the ground to effect the removal of carbon or other extraneous deposit therefrom.

Another salient object of the invention resides in providing said valve stem with a co-operative device for imparting friction thereto, said device being of such nature 35 as to retain the valve stem inert and to overcome the momentum thereof during the period of travel of said gear element from one of said pinions to the other, in order that the teeth of said pinions will be maintained in 40 such positions as to readily mesh with the teeth of the gear element, and to thereby avoid the possibility of binding or tooth locking between the gear element and pinions so that the grinder will be constantly 45 maintained in condition for successful operation.

With these and other objects in view, as will appear as the description proceeds, the invention accordingly consists in the novel 50 features of construction, combination of elements and arrangement of parts to be hereinafter fully described and wherein the scope thereof is pointed out in the following claims.

55 In the accompanying drawing, forming a part of this specification, and wherein sim-

ilar characters of reference denote like and corresponding parts:

Figure 1 is a side elevation of the valve 60 grinding tool comprising the present invention.

Figure 2 is a front elevation of the tool, the cover plate thereof being omitted in order to disclose the underlying structure, and

Figure 3 is a horizontal sectional view 65 taken along the line 3—3 of Figure 1.

Referring more particularly to the structural details of the invention, the latter in this instance has been exemplified as comprising a hollow circular or drum like casing 1, 70 preferably formed from cast iron, the bottom of said casing being provided with a tubular boss 2, and the upper portion, diametrically opposite the depending boss 2 is provided with a bearing enlargement 3. A valve rotating shaft 4 is journaled for rotation within the casing 1, said shaft having its upper end suitably supported for rotation within the bearing 3 and its lower end likewise journaled within the supporting and guiding 75 boss 2. The lower end of said shaft projects below the boss 2 and is bifurcated as at 5 for the reception of a valve engaging plate 6, a cotter pin 7 being employed to pivotally fasten the plate 6 within the bifurcated portion 80 of the valve shaft, said plate as usual being provided with depending lugs 8, which are adapted for engagement with the usual socketed recesses found in the poppet valves of internal combustion engines. In this manner 85 the rotation of the shaft 4 will impart similar movement to the engine valves, whereby the latter may be employed in the ordinary manner for effecting the removal of carbon deposit upon its associated seat. 90

In order to impart the required oscillatory motion to the shaft 4, the latter is provided within the casing 1 with a pair of fixed and spaced pinions 9 and 10, these pinions being disposed for meshing engagement 100 with a gear element 11, the latter being also situated within said casing and is preferably mounted for rotation in unison upon a stud shaft 12, which latter is journaled within a tubular bearing 13 projecting from 105 the rear face of the casing. A crank arm 14 depends rigidly from the outer end of the shaft 12 and the free end of said arm is, in turn, equipped with a knob or handle 15, whereby upon the rotation of the shaft 12 110 through the medium of said knob and its associated arm 14 rotary motion may be

imparted to the gear element 11. This element is provided with teeth 16 which are of such number as to be simultaneously free from engagement with either one or the 5 other of the pinions 9 and 10, so that upon the rotation of the element 11 the teeth 16 thereof will successively engage with said pinions to oscillate the shaft 4 first in one direction and then in the other.

- 10 In order to retain the teeth of the pinions in such relation as to be capable of engaging with the teeth 16 of the element 11 without causing the said teeth to bind, use is made of a spring element 17, which has one end 15 thereof fixed as at 18 to the removable cover 19 of the casing 1, and the free end 20 of said spring element is disposed to resiliently press upon the shaft 4 so as to arrest undue motion on the part of the latter. Thus, when 20 the teeth 16 are free from engagement with either of said pinions, the rotation of the shaft 4, caused by its own momentum, will be checked by the friction exerted thereon through the co-operation of the element 17, 25 thus enabling the set condition of said pinions to be maintained so that the teeth 16 will readily intermesh with the teeth of the pinions without the liability of binding between the inter-meshing parts.
- 30 From the foregoing description, taken in connection with the accompanying sheet of drawing it will be seen that there is provided a device of considerable utility, and one fully capable of carrying out the above enumerated objects. The grinder is exceptionally light in weight and is thus capable of 35 being conveniently and simply manipulated. Again, through the instrumentality of the spring device 17 the life of the grinder is

considerably prolonged, inasmuch as means 40 have been provided for preventing unnatural binding between the gears of the tool and the liability of fracture, which is always present when such binding occurs, pre- 45 cluded.

What I claim is:

1. In a valve, a casing, a valve rotating shaft journaled in said casing, a pair of spaced pinions carried by said shaft, a gear element capable upon being revolved of 50 successively meshing with said pinions to alternately oscillate the shaft first in one direction and then in the other, a removable closure plate for said casing, and a leaf spring having one end thereof fixed to said 55 plate and its opposite or free end disposed to engage with said shaft, whereby said spring will serve to maintain said shaft substantially stationary during the period of 60 repose when the gear element is out of mesh with said pinions.

2. In a valve grinder, a casing, a valve rotating shaft journaled within said casing, a pair of spaced pinions carried by said shaft, a gear element capable upon being re- 65 volved of successively meshing with said pinions to alternately oscillate the shaft first in one direction and then in the other, a removable closure plate for said casing, and friction exercising means carried by 70 said plate and disposed to engage with said shaft to effect proper meshing relation between the teeth of said pinions and those of said gear element.

In testimony whereof I affix my signature. 75

ERWIN R. JONES.
